UNITED STATES PATENT OFFICE.

DAVID SHERWOOD KENNEDY, OF BROOKLYN, NEW YORK, ASSIGNEE TO MERGEN-
THALER LINOTYPE COMPANY, A CORPORATION OF NEW YORK.

TYPE OR MATRIX.

1,221,868.

Specification of Letters Patent. Patented Apr. 10, 1917.

Application filed August 14, 1914. Serial No. 856,763.

To all whom it may concern:

Be it known that I, DAVID SHERWOOD KENNEDY, a citizen of the United States, residing at Brooklyn, in the county of Kings and State of New York, have invented certain new and useful Improvements in Type or Matrices, of which the following is a specification, reference being had therein to the accompanying drawing.

10 My invention relates to type or matrices for typographical machines, such as linotype machines of the general organization represented in Letters Patent of the United States, No. 436,532, to O. Mergenthaler. In machines of this class, the matrices are stored in a magazine, are released therefrom by the manipulation of the keyboard mechanism, are assembled in line and then presented to a mold, wherein the slug or linotype is cast. After this, the matrices are distributed and restored to the magazine from which they started.

In the ordinary form of distributor, the matrices are caused to pass along a grooved rail or bar until they reach the proper magazine channels, into which they drop in the manner well understood in the art. It sometimes happens that a matrix will not drop directly thereinto, but is displaced or tilted to such an extent that it is caught and held, ordinarily in the channel entrance. This tilting or failure of the matrices to drop directly is caused in several ways, but chiefly by the fact that just at the moment they are released from the grooves of the distributor rail, there is a tendency for them to pivot or swing about their supporting teeth, and this tendency is emphasized and increased in the case of the thicker matrices, whose teeth are located at one side thereof and consequently well beyond the center of gravity.

To correct the difficulty, I form the matrix with its teeth immediately above its center of gravity and in a vertical plane between the side faces thereof, which construction not only obviates the tilting already mentioned, but in addition tends to insure the correct guiding and location of the matrices throughout the operation of the machine. It will of course be understood that the distributor bar, or the other elements engaged thereby, will be correspondingly formed to permit the disengagement of the matrices therefrom at the proper points, thus insur-

ing their delivery in a straight line and directly into the magazine entrance and magazine.

I have illustrated my invention as applied to an extremely large or thick matrix, but obviously it can also be adapted to matrices of smaller size, and many other changes and variations may be made therein, and in its mode of application, which will still be comprised within its spirit. Similarly, the invention may be adapted to type or dies, as well as to matrices. Generally speaking, I desire it to be understood that I do not limit myself to any specific form or embodiment, except in so far as such limitations are specified in the claims.

70 Referring to the drawing:

Figure 1 shows a portion of a distributor bar and my improved matrices coöperating therewith; and

75 Figs. 2, 3 and 4 are respectively perspective, sectional, and top views of the matrix itself.

The matrix X, which is of the thick or "display" variety, is formed between the side faces thereof with the usual toothed web or combination X¹ of less thickness than the body portion. However, in the present instance it will be noted that the teeth or web is located above and in the same vertical plane with the center of gravity of the matrix, as best shown in Figs. 2, 3 and 4. In Fig. 1, two such matrices are illustrated, one sustained by the distributor bar A, it being held in engagement with the ridges A¹ thereof in the usual manner, and the other released therefrom and passing into the channel B. Due to the described location of the toothed combination X¹ with reference to the center of gravity and other portions of the matrix, the tendency to tilt is obviated, and as the matrices arrive at the corresponding combinations on the bar, they pass therefrom directly and in vertical planes into the underlying channels.

100 As previously stated, I have shown my invention only in preferred form and in a special application, but obviously many modifications and alterations therein, and in its mode of adaptation, will suggest themselves to those skilled in the art, without departure from its scope.

Having thus described my invention, its construction and mode of operation, what I

claim and desire to secure by Letters Patent of the United States, is as follows:

- 5 1. An integral type or matrix formed with a sustaining portion of less thickness than that of its body and definitely located in a plane passing vertically through its center of gravity whereby such center of gravity of the matrix and the plane of the combination will be in the same vertical line.
- 10 2. An integral type or matrix having distributing teeth formed in a portion of less thickness than that of its body and definitely

located in a plane passing through its center of gravity, whereby the matrix when suspended by such distributing teeth will be in 15 a direct vertical plane and in alinement with the plane of the teeth.

In testimony whereof, I have affixed my signature in presence of two witnesses.

DAVID SHERWOOD KENNEDY.
